UNITED STATES PATENT OFFICE.

SYLVAIN DE JONG, OF ANTWERP, BELGIUM.

APPARATUS FOR TRUING GRINDING WHEELS FOR GRINDING GEAR-WHEEL TEETH.

Application filed August 14, 1924. Serial No. 732,098.

To all whom it may concern:

Be it known that I, SYLVAIN DE JONG, engineer, a subject of the Queen of the Netherlands, residing at Antwerp, Belgium, 23 Avenue Van Put, have invented new and useful Improvements in Apparatus for Truing Grinding Wheels for Grinding Gear-Wheel Teeth, of which the following is a specification.

10 The present invention relates to an improved apparatus for truing grinding wheels for use in grinding the faces of gear wheel teeth, and in order that the said invention may be readily understood, an 15 embodiment of the said apparatus is, by way of example only, illustrated by the accompanying drawing, wherein:

Fig. 1 is a perspective view showing the complete apparatus according to the invention with the parts in the position which they occupy for truing one face of the grinding wheel,

20 Fig. 2 is a similar view, showing the parts in the position which they occupy for truing the other face of the grinding wheel,

25 Fig. 3 is a perspective view showing the gear wheel of which the teeth have to be ground in position in relation to the grinding wheel, and

30 Fig. 4 is a detail at an enlarged scale.

Referring to the said drawing, the apparatus according to the invention substantially comprises a yoke member *a* carrying the diamond-holder *c* and of which one end is connected by means of a universal joint *b* to a spindle *m* which is placed between the centres *e* and *g* of the machine which normally serves for grinding the faces of the gear wheel teeth. The other end of the 35 yoke-member *a* is provided with a finger *i* which engages and follows the contour of a template disc *d* which is integrally mounted on the spindle *m* and determines the contour of the teeth, of which the 40 development is amplified in order to correct the differences which might be present 45 on a small curve which is difficult to obtain with accuracy.

The diamond-holder *c* carrying the diamond is placed centrally between the fixed point of articulation of the yoke-member *a* and the template disc *d*.

50 Means may be provided to obtain a most accurate adjustment for the position of the diamond so as to secure a dead true alinement between the centre of articulation-

joint *b*, the point of the diamond *c* and the knife edge of the finger *i* following the template disc *d*. The diamond may thus quite readily be placed in the position 60 which it should occupy to obtain an exact reproduction of the contour of the template disc *d*, and the small amount of wear of the diamond may also be practically and rapidly compensated. The spindle *m* is 65 provided with two drivers *n* placed at its two ends but in diametrically opposite direction, so that the apparatus as a whole may readily be reversed between the centres *e* and *g* (see Figures 1 and 2 respectively) in 70 order to allow the truing of both faces of the grinding wheel in an absolutely symmetrical manner and with a complete identity of shape and position in relation to the aligned centres *e* and *g*.

75 The spindle *m* is placed between the said centres exactly in the place and stead of the spindle carrying the work.

The angular setting of the apparatus between the centres is of no importance as far 80 as the correction of the tooth profile to be ground is concerned, as the profile of the grinding wheel is always trued in a mathematical exact relation to the centres carrying the work; and therefore the thickness 85 of the grinding wheel may vary, from the full width of the tooth space, to any width less than the tooth space, as long as the outer edge of the grinding wheel is strong enough not to crumble away. This is shown 90 in Figure 4.

The described apparatus, which is simple and light, may readily be applied for truing the grinding wheel of a battery of machines simultaneously, and does not take any 95 more time than putting an ordinary mandrel between the centres. The said apparatus thus enables a maximum production to be obtained.

The operation of the apparatus referred 100 to will be readily understood from the above description.

The apparatus as a whole is placed between the centres *e* and *g*, without clearance, the driver *n* being inserted in the carrier *p* 105 of the dividing head; it will then be sufficient to bring the diamond in contact with the grinding wheel by effecting the angular adjustment of the driver in relation to the carrier by means of the two set screws *r* 110 and to cause the follower finger *i* to follow the contour of the template disc *d* until the

grinding wheel is properly touched for the complete curve. Then, without changing anything either to the grinding wheel or to the relative adjustment of the driver and carrier, the apparatus as a whole should be merely reversed between the centres when the other side or face of the grinding wheel has to be trued in turn.

It should be understood that the axis of 10 the grinding wheel may be lowered in relation to that of the centres of the machine as the grinding wheel wears, but a truing of the grinding wheel in this case is necessary before the work is put in position.

15 The contour of the grinding wheel is thus obtained in a perfect manner with a single template disc and a single diamond.

I claim:

In an apparatus for truing grinding-wheels for grinding the profile of gear wheel teeth, to be used in connection with a machine for grinding gear-wheel teeth normally comprising a removable spindle carrying the gear-wheel to be ground, the com-

bination of a spindle adapted to be mounted 25 in the said machine coaxially with the axis thereof and having its own axis extending through a fictitious point corresponding to the geometric centre of the pitch circle of the gear-wheels to be ground, a template 30 disc fixed on one end of the last-named spindle, a yoke-member having one of its ends connected to the other end of said last-named spindle by means of a universal joint, a follower finger fixed to the other end of said 35 yoke-member and engaging the periphery of the template disc, and an adjustable diamond-holder mounted centrally in the said yoke-member and fitted with a diamond, substantially as described. 40

In testimony whereof I signed hereunto my name in the presence of two subscribing witnesses.

S. DE JONG.
